(57) **CLAIM**

The ornamental design for a docking station with a transparent stand on the front, as shown and described.

DESCRIPTION

FIG. 1 is a top front perspective view of a docking station with a transparent stand on the front showing my new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof;
FIG. 7 is a bottom plan view thereof; and,
FIG. 8 is a right side view thereof showing that a tablet computer is docked on the stand of the present docking station.

The broken lines in the drawings illustrate portions of a docking station with a transparent stand on the front which form no part of the claimed design.
